DRESSMAKER'S PEDESTAL

Ruby G. Mayo, Los Angeles, Calif.

Application June 12, 1946, Serial No. 676,311

2 Claims. (Cl. 33—10)

1

This invention relates to a dressmaker's pedestal and has for its primary object to provide a device for facilitating pinning or folding a dress or coat hem on a figure or model.

Another object of the present invention is to provide a dressmaker's pedestal embodying vertically and laterally adjustable means about which a hem is adapted to be formed according to the height of the hem from the floor and the fullness of the skirt.

Another object of the invention is to provide simple and improved means guiding the forming of a dress or skirt hem, said means being adjustable and removable from the garment after the hem is pinned or otherwise secured.

Another object of the invention is to provide a dressmaker's pedestal which is rotatable to cause progressive rotation of the figure or model whereby the hem can be progressively moved with respect to the operator and thereby facilitating the forming thereof.

My invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a top plan view of a dressmaker's pedestal embodying the present invention.

Fig. 2 is a vertical sectional view thereof as taken on the line 2—2 of Fig. 1.

Fig. 3 is a plan sectional view as taken on the line 3—3 of Fig. 2.

Fig. 4 is an enlarged fragmentary detail face view of a band for guiding the forming of a hem and showing support means therefor.

Fig. 5 is an edge view thereof.

The dressmaker's pedestal which is shown in the drawing comprises, generally, a fixed base 10, a relatively rotatable platform 11 mounted thereon, means 12 for effecting said rotation, vertically adjustable means 13 carried by the platform 11; means 14 carried by the means 13 adapted for guiding the forming of a hem of a garment on a figure or model standing on the

2

floor 23, means 15 for effecting the mentioned vertical adjustment, and means 16 for laterally adjusting the means 14 in accordance with the fullness of the garment being hemmed.

5 The base 10 comprises a base plate 17 which is shown supported on mounting feet 18 and is provided with an upstanding tubular wall 19. The upper end of the wall 19 mounts a plurality of rollers 20 or the like which are carried on horizontal axes and serve to support the pedestal 11.

The platform 11 comprises a tubular wall 21, somewhat enlarged at its bottom end, and fitted with a ring 22 which has direct bearing on the rollers 20. A floor 23 is provided at the top of 15 the platform and serves to support a figure or model wearing the garment to be hemmed. A bottom wall or spider 24 is provided at the bottom of the platform and, intermediate its height another wall or spider 25 is provided.

20 The means 12 comprises a bevel gear 26 carried centrally of the wall 24 and, therefore, axially of the base or pedestal, a bevel pinion 27 in mesh with said gear, a shaft 28 extending from the pinion radially through the wall 19, and a crank 25 handle 29 on the outer end of the shaft. It will be evident that the platform can be rotated by manipulation of the handle 29.

The means 13 comprises a plate 30 within the platform 11, guide rails 31 carried by the wall 21, three or more standards 32 mounted on said plate 30, a clip 33 on the upper end of each standard, and a separable band 34 carried by the clips. The standards 32 extend through openings 35 in the floor 23 so that the band resides on the outer side of said floor. The means 14, includes the 35 circular band 34 which comprises a flexible metal strip formed with a loop 36 at one end to receive and to enable the other and free end to slide therethrough as the band is expanded or contracted to vary its diameter. Each clip 33 is formed with an eye 37 through which the band 34 is freely movable yet firmly supported, said eye being somewhat offset with respect to the standard engaging portion 38 of the clip. Thus, the 40 eye of each clip is spaced from the standard as best seen in Fig. 5 and depends from the portion 38.

The means 16 may vary. As shown, said means 45 comprises an inwardly bent foot 39 of each standard and a guide strap or clip 40 secured to the upper side of the plate 30 and engaging the foot 39 to hold the standard vertical. Each foot 39 may bear graduations 41 for determining the extent of adjustment relative to the plate 30 and floor 23 of the standards relatively to each other

and thereby varying the circumferential dimension of the band 34 carried by the standards, the free end of said band sliding freely through the loop 36, when the adjustment of the standards is being made and the band is consequently expanded or contracted in accordance with the perimeter of a hem. The wall 21 of the platform is provided with access openings 42 whereby the mentioned adjustment can be effected.

The means 15 comprises a rigid screw threaded stem 43 extending down from the plate 30, a bevel gear 44 internally threaded for the stem and rotationally mounted on the wall 25 at its center and held against endwise movement, a bevel gear 45 meshed with the gear 44, a radially extending shaft 46 mounting the gear 45 and extending through the wall 21, and a knob or handle 47 on the outer end of shaft. Manual rotation of the knob 47 will cause rotation of the gear 44 and result in vertical movement of the plate 30 which is held by the guides 31 against rotation. Thus, the means 14 carried by the plate 30 is vertically adjustable with respect to the floor 23 to be set according to the desired distance of the hem from the floor.

The pedestal above described may have a fixed position in use but is rendered portable by a pair of handles 48 fixed on opposite sides of the base 10 as shown.

In use, a model or figure wearing the garment to be hemmed is placed on the pedestal floor 23 and the means 14 and 16 adjusted in accordance with the desired height of the hem and the circumference of the skirt or garment. Height adjustment is facilitated by graduations 49 on each standard which may be read in connection with the upper surface of the floor. The skirt material is then folded around the band 34 and pinned or otherwise secured. The mentioned offset of the clip eyes 37 permits such folding of the hem around the clips as shown in Fig. 5. The operator may maintain a stationary position and by turning the crank handle 29, rotate the platform and the model thereon to bring unhemmed portions of the garment to him for hemming. After the hem has been formed, the free end of the band 34 is disconnected from the loop 36 at the other end of the band, which may then be withdrawn from the formed hem. Those portions of the hem which are engaged over the clips are then slipped down and released from the clips.

The pedestal proportions may vary. The diameter-height ratio may be made to accord with the minimum height necessary for obtaining the height adjustments of the band with relation to the floor. Although the platform rotating gearing and the band adjusting gearing have been shown as separate mechanisms separately controlled, said gearing can be combined as a single mechanism controlled by one handle or knob and embodying suitable shift means for selective operation. A more compact device may be obtained thereby.

While I have illustrated and described what I now regard as the preferred embodiment of my invention, the construction is, of course, subject

to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. A dressmaker's pedestal comprising, in combination, a fixed base, a housing having a flat top constituting a platform, roller and track means supporting said housing above the base, manually operable means extending radially from said base and including gearing connected to the housing for rotating the latter relative to the base, a plate within said housing and guided thereby for movement toward and from the platform, means interconnecting said plate and housing for adjusting the former and including a single operating handle extending radially outward from said housing below the platform thereof, spaced relatively adjustable standards carried by said plate and extending freely through the platform of the housing, and an adjustable band carried by the extending portions of the standards above the platform.

2. In a dressmaker's pedestal, a rotationally mounted housing terminating at the top in a platform having uniformly arranged spaced openings therethrough, a wall closing the bottom of said housing and spaced from the platform, a plate in the housing between the wall and platform, guides for said plate carried by the housing to hold said plate non-rotationally with respect to the housing yet rotationally with the housing, means to adjust said plate toward and from the platform and carried by said bottom wall, said means including a handle extending laterally outward of the housing, a set of standards adjustably carried by said plate and extending through the mentioned openings in the platform, and an adjustable band carried by said standards above the platform.

RUBY G. MAYO.
